UNITED STATES PATENT OFFICE

WILLIAM HERBERT EXLEY, OF MARKET HARBOROUGH, ENGLAND

APPARATUS FOR ELEVATING ACIDS AND OTHER LIQUIDS

Application filed June 10, 1929, Serial No. 369,322, and in Great Britain June 12, 1928.

This invention relates to apparatus for elevating acids and other liquids and more particularly liquids of a corrosive nature where moving parts such as pump pistons in contact with the liquid are objectionable and a source of constant trouble. The object of the invention is to provide an apparatus which will act in effect like a pump, using compressed air, or other gases under pressure, or steam 10 as the operating medium.

The invention consists broadly in the provision of one or more containers having inlet and discharge openings and means whereby each container is alternately filled with liquid and supplied with gas under pressure so as to force out the liquid through the discharge openings.

Some of the forms which the invention may take are illustrated in the accompanying 20 drawings in which:—

Fig. 1 shows diagrammatically a vertical section through one embodiment of the invention.

Fig. 2 shows a vertical section through the 25 junction of the discharge pipes in another embodiment of the invention.

In the construction shown in Fig. 1 two cylindrical, or other suitably shaped containers 1 and 2 of lead, ebonite, porcelain or other suitable material are immersed in the liquid to be elevated and are provided with inlet valves so arranged that when pressure is applied to the inside of either container its 30 valve automatically closes. These valves may consist of rubber balls 3 and 4 resting on seatings 5 and 6 made from the same material as the container, or of glass balls resting on rubber seatings, or any other suitable combination. Guards 7 and 8 are provided 35 to prevent the balls floating off.

Each container is provided with a discharge pipe 9 and 10, extending from the lowest point of each container upwards 40 through the containers, or outside them, to

the delivery pipe 11 into which it is desired to lift the liquid.

Pressure pipes 12 and 13 are fitted to the highest point of each container and are connected to opposite sides of a two way control valve or cock one position of which applies pressure to the inside of one container and at the same time connects the inside of the other to the atmosphere and vice-versa when the control valve is moved to the other position. 55

The body of the control valve is formed in two portions 14 and 15 and is in communication, through the pipes 12 and 13, with the containers 1 and 2 and, through a pipe 60 16, with a source of compressed air or other gas under pressure. A rod 17 is slidably mounted within the body of the valve and carries a ball 18 of rubber or other suitable material which is secured thereon between a 65 pair of tubular sleeves 19 and 20 which are provided with longitudinal slots 21 and 22. The rod 17 also carries rubber washers 23 and 24 which are secured by metal washers 25 and 26 and nuts 27 and 28. 70

When the valve is in the position shown in the figure the rubber ball 18 cuts off the supply of compressed air, delivered through the pipe 16, from the pipe 13 and thus from the container 1. The container 1 is however 75 in communication, through the pipe 13 and the slots 21, with the atmosphere. The pressure of the liquid will thus lift the ball 3 and the container will fill with liquid.

At the same time the container 2 is in communication with the source of compressed air through the pipes 12 and 16. The slots 22 do not extend to the atmosphere and the bearing of the rod 17 is further sealed by the rubber washer 24. Any liquid there may be 80 in the container will thus be forced up the discharge pipe 10 into the pipe 11. When all the liquid from the container 2 has been forced through the discharge pipe into the delivery pipe the sudden acceleration of air 85 90

- in the system moves the ball valve 18 to the right cutting off the supply of compressed air from the container 2 and opening it to the atmosphere. At the same time the container 1 is shut off from the atmosphere and supplied with compressed air through the pipe 13, so discharging the contents of the container 1 through the pipe 9 while the container 2 is being filled.
- 10 Instead of using two rising pipes, both discharge pipes 9 and 10 may be connected to a check valve, a vertical section through which is shown in Figure 2.

15 The discharge pipes 9 and 10 open into the space within the body 30, and the opening of either of them may be sealed by the rubber ball 31. The interior of the valve is in communication with a vertical delivery pipe 11. A guard 32 is provided at the mouth of this 20 pipe to prevent the ball 31 from floating off.

25 When the liquid is being discharged from one of the containers through the pipe 9 the ball is forced to the right, sealing the pipe 10 and preventing the liquid from flowing back 30 into the other container. All the liquid is thus forced up the delivery pipe 11. When all the liquid has been forced out of this pipe the air supply control valve operates as above described and liquid is then forced from the other container through the discharge pipe 10; the ball 31 is forced to the left and seals the opening of the pipe 9. All the liquid is thus forced up the pipe 11.

35 What I claim and desire to secure by Letters Patent is:—

1. Apparatus for elevating liquids comprising a pair of containers adapted to be immersed in the liquid to be elevated, an inlet to each of said containers, an automatic non-return valve controlling each of said inlets, discharge pipes leading from each of said containers to a common discharge main, separate pipes for conducting elastic fluid pressure to each of said containers, a main 40 pipe conducting elastic fluid pressure from a source of supply to each of said separate pipes, a valve chest to and from which said main and separate pipes lead, and having ports to which said separate pipes are coupled, a ball valve, a slidable spindle on which said valve is fixedly mounted, said spindle passing longitudinally through said chest and operating to close each of said ports alternately, a sleeve valve mounted upon each 45 end of said slidable spindle so as to move together with the ball valve and having ports which connect each of the separate pipes to atmosphere by back pressure when said ball valve operates to shut off the supply of elastic 50 fluid pressure to such pipe.

- 55 2. Apparatus for elevating liquids comprising a pair of containers adapted to be immersed in the liquid to be elevated and each having an inlet, an automatic non-return valve controlling each of said inlets, a

common discharge main, discharge pipes leading from each of said containers to said common discharge main, a main pipe for conducting elastic fluid pressure from a source of supply to each of said separate pipes, and an oscillating valve member between said main and separate pipes and directly exposed to the flow of elastic fluid, said valve member operating to connect each of said separate pipes alternately to the atmosphere and the main pipe and being actuated solely by the acceleration of the elastic fluid flowing past it.

In witness whereof I affix my signature.

WILLIAM HERBERT EXLEY.
